C. A. SOUTHWICK.
AUTOMATIC WATER FEEDER.

No. 518,866.

Patented Apr. 24, 1894.

UNITED STATES PATENT OFFICE.

CHARLES AUSTIN SOUTHWICK, OF PEABODY, MASSACHUSETTS.

AUTOMATIC WATER-FEEDER.

SPECIFICATION forming part of Letters Patent No. 518,866, dated April 24, 1894.

Application filed September 2, 1891. Serial No. 404,514. (No model.)

To all whom it may concern:

Be it known that I, CHARLES AUSTIN SOUTHWICK, of Peabody, in the county of Essex and State of Massachusetts, have invented new 5 and useful Improvements in Automatic Water-Feeders, of which the following is a specification.

This invention relates to automatic water-feeders of the class to which my Letters Patent No. 384,874, granted June 19, 1888, belongs, for the purpose of maintaining a standard level of water or other liquids in steam boilers, tanks, &c., and it consists in certain improvements and combinations of parts whereby greater efficiency, economy, and equality of 15 wear, are secured, and repairs rendered more easy.

In the accompanying drawings, in which similar letters of reference indicate like parts, 20 Figure 1 represents a vertical section of my improved water-feeder, certain portions being shown in broken lines. Fig. 2 is a section on line *x* Fig. 1. Fig. 3 is an enlarged section on line *y*, Fig. 1, a portion only of the 25 sliding valve *R* being shown.

A A' represent the feed-reservoir which is a closed vessel divided vertically at *a* into two parts and bolted together, as shown, so that the part *A'* can be readily removed for purposes of repairs. This reservoir is substantially of the shape shown and may be supported by a standard *a'*.

B is a float within the reservoir provided with a hole or tubular passage *B'* through its 35 diameter, through which loosely extends the rod *b*. This rod has its opposite ends secured in the arms *C'* of the swinging frame or lever *C*, which is pivoted at *C''* to the reservoir by means of the horizontal shaft *D* to 40 which it is rigidly secured, and which is supported by the reservoir, as shown in Fig. 2. Fast on the shaft *D*, is a tilting frame consisting of the side rails *E* and lower bar *E'*, in which rolls freely the ball *F*. A balance 45 weight *F'* is pivotally secured within the case *A* upon the pin *F''* and has integral with it a projection *F'''* from which extends the engaging pin *e*,—the object being to counter-balance the weight of the valve-rods and their 50 connections, (below described.)

H is a vertically reciprocating frame or connecting bar which connects the two valve-

rods *g* and *h*. This frame engages the counterbalance *F'* by means of a notch or opening *H'* into which the said pin *e* projects, and the frame *H* is engaged by the swinging frame *C* by means of a pin or roll *c* extending from said swinging frame into the long vertical opening *H''* in the valve-rod frame *H*.

I is a valve-shell secured to the under side 60 of the reservoir *A A'*, as shown, and leading into it by means of the opening *I'* which is coincident with the opening *A''* in said reservoir. This valve-shell is provided with an internal chamber *J* whose tubular portion *J'* 65 serves as a guide for the tubular valve *l* secured to the lower end of the valve-stem *g* by means of the open frame *g'*, said valve-stem being adjustably secured to the lower end of the vertically reciprocating frame or 70 rod *H*, and playing in the guide *g'* secured to the reservoir.

K is the water inlet leading into the internal chamber or shell *J* by means of the opening *K'*, and *L* is the water outlet which by 75 means of a suitable pipe (not necessary to be shown in the drawings) leads to the boiler, tank, or receiver of any kind in which a standard level or height of liquid is to be maintained. The outlet *L* is connected with the 80 inner shell or chamber *J* by means of the opening *L'*. It will readily be seen that while the valve *l* is in the position shown in Fig. 1, the inlet *K* is open, and water is free to enter through said inlet, opening *K'*, and openings *I'* and *K''* to the reservoir, while the outlet *L* is closed. If the valve *l* were to be raised, the water-inlet *K* would be closed and the water-outlet *L* would be opened, allowing water to pass from the reservoir through the 90 openings *A''* and *I'*, tubular valve *l*, opening *L'* and outlet *L* into the pipe leading to the boiler. The downward movement of the valve is limited by the seat *l'* which is touched by the open frame *l''* extending from the 95 lower end of the valve.

N is a valve-shell secured to the upper side of the reservoir *A A'* and provided with a removable cap *N'*. This shell is provided with an internal horizontal ledge or valve-seat *n* 100 which has openings or ports *n'* therein, such openings leading from the portion of the interior of the shell next the cap *N'* to the main portion of the interior which is connected

with the reservoir A A' by the opening A'''. A steam-inlet P leads into the portion of the shell above the ledge or valve-seat n, and a sliding valve R, provided with suitable openings or ports R', is held down upon the valve-seat n by means of a spring S. To the upper end of the frame or valve-rod connection H is adjustably secured the lower end of the valve-rod h, and the upper end thereof is 5 pivotally secured to the elbow-lever or bell-crank m which is pivoted at m' to the shell N. This bell-crank m is provided with a sleeve or sliding tube t which slides upon the vertical rod T which extends down from the 10 sliding valve R through one of the openings n' in the valve seat n. When this valve is in the position shown in Fig. 1, steam cannot pass from the inlet P into the reservoir as the openings or ports R' and n' are not coincident, but should the valve-rod h be raised, the valve R would be slid back by means of the bell-crank m, sleeve t and rod T, making the ports R' and n' coincident and allowing steam to pass through them into the shell N 15 and thence through the opening A''' into the reservoir A A'.

U is an exhaust opening into the atmosphere.

In practical operation therefore, the water 20 enters the inlet K and passes in the manner above described into the reservoir, raising the float B until it strikes the upper arm C' of the swinging frame, which then proceeds to swing upward until the pin c strikes the upper edge of the opening H'' in the valve-rod frame or connection H. This motion raises the right hand end of the tilting frame E E' until at the instant the pin c touches the upper end of the opening H'' the ball F rolls to 25 the left hand and assists the upward movement of the valve-rod frame H. This operation moves the sliding valve R so that the ports are opened for the admission of steam from the steam-inlet P and closed to the exhaust V, thus letting steam into the reservoir, and at the same time it closes the water-inlet K and opens the water-outlet L. As the water in the reservoir lowers, the above op- 30

eration is reversed, and by this means a standard level is maintained in the boiler which is 50 connected by a suitable pipe with the outlet L. The interior of the valve-shell N is easily accessible by removing the cap N'.

The steam and water pipes connecting with the boiler are similar to pipes c and f in my 55 Letters Patent above referred to.

Having thus fully described my invention, what I claim, and desire to secure by Letters Patent, is—

1. In an automatic water feeder, the combination of the reservoir A, the valve shell N secured to the upper side thereof and provided with the internal horizontal ledge or valve seat n having the openings or ports n' and steam inlet P, the sliding valve R provided with the ports R' and held down upon the valve seat by the spring S, the cap N', the bell crank m pivoted to the shell, the vertical rod T extending down from the sliding valve R through one of the openings in the 70 valve seat, the sliding tube t on said vertical rod, the exhaust U, the valve rod h, and actuating mechanism, constructed and arranged substantially as set forth.

2. In an automatic water feeder, the combination of the reservoir A, the valve-shell I and internal shell J provided with the tubular portion J', said tubular portion having the ports K' L', the water-inlet K, water-outlet L, tubular valve l, and valve-rod g, all constructed and arranged substantially as described.

3. In combination, the valve-rods h g, the reciprocating valve-rod frame H connecting said valve-rods, said frame provided with the opening H'' and notch H', the swinging frame 85 C C' pivoted to the reservoir and engaging the frame or stem H by means of the opening H'' and itself engaged by the float B sliding on the rod b held by said frame C C', the tilting-frame E E' sustaining the ball F and actuated by the shaft D, and the reservoir, substantially as set forth.

CHARLES AUSTIN SOUTHWICK.
